METHOD OF AND APPARATUS FOR SPOOL-
ING HEELSMerton W. Howard, Haverhill, Mass., assignor to
Pope Machinery Corporation, Haverhill, Mass.,
a corporation of Massachusetts

Application May 9, 1936, Serial No. 78,891

17 Claims. (Cl. 12—47.1)

This invention relates to a method of and apparatus for rounding the sharp edges produced at the intersections of the turned and breasted surfaces of a heel, this operation being commonly known as "spooling".

An object of the invention is to provide a simplified spooling machine for hand operation, that is, manual manipulation of the heels, the machine being so designed as to enable the operator to compete with automatic or semi-automatic spooling machines in average rate of production. In heel spooling machines of the hand type, the machine must first be adjusted to operate on the size and style of heel to be spooled. When the machine is adjusted and ready for operation, each heel must be picked up from the receptacle by hand, mounted on a suitable jack, moved into operative engagement with one or more forming cutters which act to round off the edges at the sides of the breast of the heel, and then transferred from the jack to a suitable container. The last step must be carefully carried out since the heels are easily damaged and must not be dented or nicked. It is an object of the present invention to provide heel-spooling mechanism which is capable of quick and easy adjustment for operation on heels of different styles and sizes. It is a further object of the invention to facilitate the handling of heels so that the spooling operations can be carried out in rapid succession, the heels being delivered to a receptacle in such a manner as to avoid injury to the sharp edges or corners thereon.

In the embodiment of the invention herein-after described, a pair of spaced form cutters are provided, these cutters being mounted above a work table on which a jack is freely slideable in any direction. Various adjustable gages or stop elements are mounted on the table so as to limit the range of movement of the jack and thus to confine the jack to such movements as are necessary for the spooling operation. The table is also preferably provided with an aperture near the form cutters, this aperture being located so that, when a heel blank has been spooled and retracted from the cutters, it will be directly over the aperture. The jack includes a heel-supporting portion against which a heel must be manually held in an unstable position, so that, when the heel is released, it immediately falls from its support. Thus, when a heel has been spooled and retracted from the form cutters, the release of the heel allows it to fall from the jack through the aperture in the table. Under the aperture a sloping surface, such as a suitable

chute, may be provided to receive the heel and to conduct it out to one side of the machine where it can be deposited in a receptacle without injury.

For a more complete understanding of the invention, reference may be had to the description of an embodiment thereof which follows, and to the illustration thereof on the drawings of which

Referring to the drawings in detail, the embodiment of the invention illustrated therein includes a work table 20 which is preferably horizontal and may be supported in any suitable manner as by legs or standards 22. The standards 45

22 may, if desired, be a part of the frame 24 on which is also mounted a suitable motor 26. The motor drives a pulley wheel 28 which is connected by a suitable belt 30 to a pair of pulley wheels 32 mounted on shafts 34 which project upward 50 through the table 20. At the upper ends of the shafts 34 are mounted forming cutters 36 of the rotary type, these cutters being suitably spaced above the surface of the table 20. As the cutters 55 are preferably driven at high speeds, the shafts

34 are provided with suitable high-speed bearings enclosed in casings 38 beneath the table 20.

The table 20 may be provided with a suitable aperture 40, preferably near the cutters 36, this aperture being of sufficient size to receive easily a heel. Below the aperture 40 a chute 42 is provided, this chute having an inclined bottom adapted to receive heels and to conduct them to one side of the machine where they can be deposited in a suitable receptacle. As indicated in Figure 3, a suitable deflector 44 may be mounted under the portion of the aperture nearest to the cutters so as to deflect the heels from the bearing housings 36 to guide them into the chute 42. As shown, the deflector plate 44 and the chute 42 may be lined with soft material such as felt so as to avoid bruising or nicking the sharp edges or corners of the heels.

In order to facilitate movement of heels into and out of engagement with the cutters 36, a suitable jack is provided to slide freely on the surface of the table 20. As shown, this jack may comprise a frame 50 including a pair of arms 52 and 54 which extend toward the rear of the table and are spaced apart to span the aperture 40 and to straddle the shafts 34. The jack frame 50 may be a casting or may be otherwise produced. Integral therewith or permanently secured thereto is an upright lug or ear 56 having a boss 58 through which passes a bolt 60. This bolt also extends through a slot 62 in a bracket 64 projecting from the rear face of the plate 66 and perpendicular thereto. The plate 66 is the element against which the seat face of a heel rests when the heel is in position on the jack, and is pivotally mounted on the frame 50 as at 68. The slot 62 is arcuate, its center of curvature being the axis of the pivot 68, so that, when the nut on the bolt 60 is loosened, the plate 66 can be adjusted to any desired angle of inclination. Tightening up the bolt 60 will then retain the plate 66 in such an angular adjustment. A suitable scale 70 may be provided on the bracket 64 to facilitate adjustment of the plate 66 to previously determined angles of inclination.

As indicated in Figure 4, the plate 66 is centrally slotted to receive a sliding element 72 on which is mounted a transverse breast stop 74. The upper end of the slide 72 is drilled and tapped as at 76 to receive an adjusting screw 78 mounted in the upper end of the plate 66. By turning the screw 78, the breast stop 74 can be given slow motion adjustment so that the heels supported on the jack can be brought to exactly the right elevation above the table surface for proper engagement with the forming cutters. The breast stop 74, illustrated in Figures 4 and 5, is designed for use with heels of the Cuban type, the length of this breast stop being less than the width of the heel breast. In heels of this type, the breast surface extends in cylindrical form to its intersection with the seat surface, the line of intersection being thus arcuate. In order to ensure that the heel on the jack will be properly held and not inclined to one side or the other, the heel must be carefully centered with respect to the breast stop 74. To provide for such centering, an adjustable side gage element 80 is mounted on the plate 66, this element being engageable by a side edge of the seat face of the heel. A setscrew 82, extending through a slot 84 in the element 80, can be loosened to permit adjustment of the gage

element 80. The element 80 need not be adjusted for Louis heels but is useful in facilitating the mounting of such heels in position on the plate 66 for the spooling operation. Figure 6 shows a lip stop 86 suitable for heels of the Louis 5 type, this lip stop being preferably longer than the lip of the heel.

Suitable guides are mounted above the cutters 36 to limit the approach of the heel to the cutters and thereby to prevent the removal of too much material from the heel blank in the spooling operation. These guides may be formed as desired and supported by any suitable means. As indicated in Figures 1 and 7, each cutter guide consists of an arm 94 carrying a fixed plate 90 and a rotatable disk 92, these being mounted so that a portion of the periphery of the disk 92 projects slightly beyond the adjacent portion of the periphery of the plate 90. The shape of the plate 90 is indicated in Figure 1, the disk 92 being provided to facilitate the movement of the heel past the cutter. The arm 94 is longitudinally slidable on the bracket 96. An adjusting screw 98 is in threaded engagement with the bracket 96 and is provided with a flange 100 engaging in a notch 102 in the arm 94, so that, by turning the adjusting screw 98, the arm 94 may be given fine longitudinal adjustment. A knurled nut 104 is threaded onto a screw 106 mounted in the end of the bracket 96 and projecting through a slot 300 in the arm 94. When the nut 104 is set up tight, the arm 94 is fixed in adjusted position. Since the guide plate 90 is directly over the end of the cutter 36, it must be moved out of the way whenever it becomes necessary to change the cutter. It is desirable, in order to save time, to be able to replace the guide plate 90 quickly and accurately in its previous position of adjustment after it has been moved aside to permit the removal or replacement of the cutter 36. To this end, the bracket 96 is provided with a vertical stud 110, which, as indicated in Figure 2, projects downward through a hole in the table 20. The reduced lower end 112 of the stud 110 is threaded to receive a nut 114. The nut presses against a spring washer 116 which holds the bracket 96 firmly against the table top so that no dust or dirt can work in between the contacting faces of the bracket and table. This structure permits the bracket 96 to be swung on a vertical axis. The bracket is normally secured in its operative position by a setscrew 120 which may be operated by a convenient handle 122 to engage the stud 110 and to clamp the stud against rotation. In order to determine accurately the proper angular adjustment of the bracket 96, it may be provided with a laterally projecting arm 124, as shown in Figure 1. Through the end portion of the arm 124 an adjusting screw 126 is threaded, this screw being provided with a locknut 128. An end of the screw 126 is adapted to abut a fixed lug 130 on the table 20. Rotation of the screw 126, while its end is pressed against the lug 130, results in a fine adjustment of the angular position of the bracket 96. When the proper position is determined, the nut 128 is set up. Then, while the screw 126 is manually pressed against the lug 130, the hand wheel 122 is turned to tighten the setscrew 120 against the stud 110, thus locking the bracket in its position. When it is desired to remove or replace the cutter 36, the hand wheel 122 is turned to release the bracket 96, the bracket then being swung so that the guide plate 90 moves clear of its cutter 36. When the

75 cutter has been replaced, the bracket 96 is swung back until the screw 126 engages the lug 130, whereupon the bracket 96 is in its former position of adjustment and may be secured therein 5 by turning the hand wheel 122. The guide plates for the two cutters are of the same construction, as are the supporting means therefor, so that the foregoing description applies to the guiding means and its support for either cutter.

10 For speed of operation, it is desirable to provide for the effective spooling of a heel during its movement through a minimum path. For this purpose, two cutters 36 are provided so that the spooling of one flank of the heel may 15 be effected during the movement of the heel into the space between the cutters, and the spooling of the other flank of the heel may be effected during the retracting movement of the heel from the space between the cutters. Thus, by a series of three brief movements, the complete spooling operation on a heel may be accomplished. These movements consist of the movement of the heel toward the rear of the table during which movement one flank of the heel is spooled, 20 a short lateral shift of the heel to bring the opposite flank into operative engagement with the other cutter, and a retracting movement of the heel toward the front of the table during which movement to the other flank is spooled and 25 the heel is returned substantially to its initial position where it can be released to fall through the aperture 40. In making these movements, the heel describes a path somewhat similar to that indicated at 136 in Figure 9. In 30 order to provide limiting means so as to prevent excessive or unnecessary extent of movement of the heel in any direction during the spooling operation, a number of stops or gages are provided, these members serving to assist 35 the operator in imparting to the jack and the heel mounted thereon only such movements as are necessary to complete the spooling operation. As shown in Figures 1 and 9, a rear stop 40 is mounted on the table. This stop is provided with an elongated edge 142 engageable by 45 the extremities of the arms 52 and 54 of the jack so as to provide a positive limit to the rearward movement of the jack. This is important as it is necessary to prevent the cutters from 50 cutting too far up on the heel. The stop member 140 is adjustable by means of a bolt 144 projecting through a slot 146 in the member 140. A front stop 150 is mounted on the table 20 near the front edge thereof and is engageable by 55 the jack to limit the movement thereof toward the front of the table. This stop is preferably adjustable toward or from the rear of the table. A side gage 152 is mounted beside the jack and is held in adjusted position by a finger bolt 153 60 the shank of which passes through a slot 155 in the gage and is in threaded engagement with the table 20. The slot 155 extends in the direction of the long axis of the gage 152 and is wider than the diameter of the shank of the bolt 65 153. Thus the gage is capable of considerable longitudinal adjustment and more limited lateral adjustment. The gage is provided with a straight guiding edge 154 which is elevated above the surface of the table so as to be engaged by a pair of roller elements 156 and 158 70 projecting up from the jack 50. The gage 152 not only serves to align the jack properly before the heel is moved into operative engagement with the first cutter, but also to determine the

path of heel movement up to the instant of initial engagement with the cutter to produce a tangential and hence shockless cutter engagement.

In setting up the machine for operation on a batch of heels, the jack is first adjusted to the size and shape of the heel to be spooled. Not more than two adjustments of the jack are necessary for a heel of the Louis type, such adjustments being to determine the angle of inclination of the supporting plate 66 and the elevation of the lip stop 86. It is not necessary to adjust the side gage 80. In the case of heels of the Cuban type, however, adjustment of the side gage 80 may be necessary in addition to adjustment of the angularity of the plate 66 and the elevation of the breast stop 74, as it is necessary that the heel be properly centered with respect to the breast stop. 15

When the jack has been properly adjusted, a heel is placed on the plate 66 and the jack is moved toward the rear of the table until the heel has progressed across the line of centers of the cutters as far as the spooling cut is to go on the flank thereof. The rear stop 140 is then moved into contact with the ends of the jack arms 52 and 54 and secured. The jack is then moved so as to bring the side of the toplift face of the heel into contact with the cutter guide element 92 at the left, the jack being held so that the line between the ends of the arms 52 and 54 is roughly parallel to the line of centers of the cutters. The side gage 152 is then moved into contact with the rollers 156 and 158 and is longitudinally adjusted until its rear end is in line with the center of the roller 158. The gage 152 is then secured in such position of adjustment. Ordinarily, no adjustment will be needed for the front stop 150, the object of this stop being merely to provide an abutment against which the jack can bring up when the heel is moved away from the right-hand cutter at the conclusion of the spooling operation. The stop 150 may be set in such position that the highest heel to be spooled will be close to the left-hand cutter when the jack is in its loading position, and left there; or, if it is desired to secure the shortest possible path length for lower heels, the stop 150 may be moved back toward the cutters to match the lesser heel height. 40

In operating the machine, little or no visual attention is required, since the guides and stops for the jack are such as to make it easy for the operator to move the jack about by the sense of touch. In one preferred method of spooling heels on this machine, heels may be picked up out of a receptacle by the left hand of the operator and held on the jack by the operator's right hand. The right hand may then be used to move the jack through the cycle of movements necessary to complete the spooling of the heel. During these latter movements, the left hand may be reached for another heel to be spooled. At the completion of such cycle of movements, the spooled heel is released by the right hand and instantly tumbles through the aperture 40 and down the chute 42. By this time the left hand of the operator has a fresh heel ready to place on the jack where it is gripped by the fingers of the right hand, as illustrated in Figure 3, for movement against the cutters in succession. 55

70 It is evident that various modifications and changes may be made in the specific embodiment of the invention herein shown and described without departing from the spirit or scope thereof as defined in the following claims. 75

I claim:—

1. In a heel-spooling machine, a table, a pair of spaced rotary cutters mounted above said table, guide elements above said cutters engageable by a heel to limit the approach of the heel to each cutter, and a heel-supporting jack freely slideable on said table to carry a heel between said cutters. 5
2. In a heel-spooling machine, a table, a pair of spaced rotary cutters above said table, drive shafts for said cutters projecting through said table, and a heel-supporting jack slideable on said table, said jack including a pair of arms projecting toward the rear of the table and spaced apart to straddle said shafts. 10
3. In a heel-spooling machine, a table, a pair of spaced rotatable shafts projecting up through said table, a rotary cutter mounted on each said shaft above said table, an adjustable stop element on said table behind and parallel to the line of centers of said cutters, guide elements over said cutters engageable by a heel to limit its approach to the cutters, and a heel-supporting jack freely slideable on said table, said jack having a pair of spaced arms extending toward the rear of the table outside of said shafts when the heel carried by said jack is moved rearwardly between said cutters, said stop element being engageable by the extremities of said arms to limit the rearward movement of a heel relative to the cutters. 15
4. In a heel-spooling machine, a table, a pair of spaced rotatable shafts projecting up through said table, rotary cutters on said shafts above the table, guide elements over said cutters engageable by a heel to limit the approach of the heel to the cutters, a heel-supporting jack freely slideable on said table to present a heel carried thereby to said cutters, and a side gage adjustably mounted on said table and engageable by two points of said jack for preliminary alinement of the jack and heel for the spooling operation. 20
5. In a heel-spooling machine, a table, a pair of spaced rotatable shafts projecting up through said table, rotary cutters on said shafts above the table, guide elements over said cutters engageable by a heel to limit the approach of the heel to the cutters, a heel-supporting jack freely slideable on said table to present a heel carried thereby to said cutters, a stop element behind and parallel to the line of centers of said cutters engageable by said jack to limit the rearward movement thereof, and a side gage adjustably mounted on said table and engageable by two points of said jack for preliminary alinement of the jack and heel for the spooling operation. 25
6. In a heel-spooling machine, a table, a pair of spaced rotatable shafts projecting up through said table, rotary cutters on said shafts above the table, guide elements over said cutters engageable by a heel to limit the approach of the heel to the cutters, a heel-supporting jack freely slideable on said table to present a heel carried thereby to said cutters, a stop element behind and parallel to the line of centers of said cutters engageable by said jack to limit the rearward movement thereof, a second stop element near the front of the table engageable by said jack to limit the movement thereof toward the front of the table, and a side gage adjustably mounted on said table and engageable by two points of said jack for preliminary alinement of the jack and heel for the spooling operation. 30
7. In a shaping machine, a table having an aperture therein, a tool mounted above said table adjacent to said aperture, and a work support 75 freely slideable on said table to present work to said spool for operation on said work by said tool, said work support including a portion against which the work is manually held in an unstable position whereby the work falls from the support when released. 5
8. In a heel-spooling machine, a table having an aperture therein adapted to receive a heel, and a pair of spaced rotary cutters adjacent to said aperture. 10
9. In a heel-spooling machine, a table having an aperture therein adapted to receive a heel, a pair of spaced rotary cutters mounted above said table near said aperture, and a heel-supporting jack normally spanning said aperture and freely slideable on said table to move a heel carried thereon into engagement with said cutters in succession and to a position in which the heel will fall through said aperture when released. 15
10. In a heel-spooling machine, a table, a pair of spaced rotary cutters above said table, and a jack slideable on said table, said jack having a heel-supporting member on which a heel may be held during the spooling operation, and guide means engageable by said jack to prevent excessive movements thereof beyond the range required for the spooling operation, said table having an aperture therein of sufficient size to receive a heel and so arranged as to be directly beneath a heel at the termination of a spooling operation. 20
11. In a heel-spooling machine, a table having an aperture therein adapted to receive a heel, a pair of spaced rotary cutters above said table and near said aperture, guide members above said cutters to limit the approach of a heel thereto, a heel-supporting jack freely slideable on said table to present a heel thereon to said cutters in succession for operative engagement therewith, and adjustably fixed guide means for limiting the range of movements of said jack on the table incident to the spooling of a heel and facilitating the return of the jack to a position in which the spooled heel is directly over said aperture. 25
12. In a heel-spooling machine, a table having an aperture therein adapted to receive a heel, means above said table for spooling a heel, a heel-supporting jack freely slideable on said table to move a heel into operative relation to said spooling means, said aperture being located with reference to said spooling means so as to be directly beneath a spooled heel as it leaves the spooling means, and an inclined surface beneath said aperture adapted to receive heels from said jack and to conduct them to a container at the side of the machine. 30
13. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, and a lip stop at the lower end of said plate. 35
14. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, a breast stop mounted on the plate, said breast stop having a breast-supporting portion shorter than the width of the breast of the heel to be spooled and an adjustable gage 40
15. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, a breast stop mounted on the plate, said breast stop having a breast-supporting portion shorter than the width of the breast of the heel to be spooled and an adjustable gage 45
16. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, a breast stop mounted on the plate, said breast stop having a breast-supporting portion shorter than the width of the breast of the heel to be spooled and an adjustable gage 50
17. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, a breast stop mounted on the plate, said breast stop having a breast-supporting portion shorter than the width of the breast of the heel to be spooled and an adjustable gage 55
18. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, a breast stop mounted on the plate, said breast stop having a breast-supporting portion shorter than the width of the breast of the heel to be spooled and an adjustable gage 60
19. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, a breast stop mounted on the plate, said breast stop having a breast-supporting portion shorter than the width of the breast of the heel to be spooled and an adjustable gage 65
20. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, a breast stop mounted on the plate, said breast stop having a breast-supporting portion shorter than the width of the breast of the heel to be spooled and an adjustable gage 70
21. A heel jack for a heel-spooling machine having a horizontal work table, said jack being slideable freely on said table, said jack comprising a horizontal base, a standard on said base, an inclined seat-supporting plate mounted on said standard and rockably adjustable thereon about a horizontal axis parallel to the plane of said plate, a breast stop mounted on the plate, said breast stop having a breast-supporting portion shorter than the width of the breast of the heel to be spooled and an adjustable gage 75

element on said plate engageable by a side edge of the seat face of a heel to center the heel on the breast stop.

15. A method of spooling heels, which comprises presenting one flank of a heel to one of a pair of rotary cutters, moving the heel in one direction when so presented to complete a spooling cut on said flank, shifting the heel to present the other flank to the other cutter, and moving the heel in the opposite direction to complete the spooling cut on said other flank.

16. A method of spooling heels, which comprises presenting one flank of a heel to one of two spaced rotary cutters for operation thereon as the heel is moved toplift end foremost into the space between said cutters, shifting the heel

laterally to present the opposite flank to the other cutter, and withdrawing the heel from said space while said opposite flank is so presented.

17. A method of spooling heels, which comprises manually holding a heel against an upright movable support, moving said heel and support to present a flank of the heel to one of two spaced rotary cutters for a spooling cut thereon, the motion of the heel being such as to cause it to enter the space between the cutters, shifting the heel and support to present the opposite flank to the other cutter, moving the heel out from between the cutters while thus presented, and releasing the heel.

MERTON W. HOWARD.
